NEUTRAL LOCK AND LATCH FOR
VOTING MACHINES

Arthur F. Foehrenbach, Ransom F. Shoup, and Charles M. Bourquin, Canton, Ohio, and Samuel R. Shoup, North Bergen, N. J., assignors of one-half to Berger Manufacturing Company, Canton, Ohio, a corporation of Ohio, and one-half to Shoup Voting Machine Corporation, Union City, N. J., a corporation of New Jersey

Application January 14, 1935, Serial No. 1,654

6 Claims. (Cl. 74—110)

This invention relates to voting machines and more specifically to a power transmission coupling therefor.

In the construction of a power actuated voting machine it is essential to provide mechanism to effect the release of the power driving unit and to provide a connection for the hand operated drive which will accommodate the ready conversion of the driving medium under unforeseen exigencies, for example, a failure in the supply of electric current during the period in which the votes are being polled.

It is also desirable in the construction of the machine to position the driving connection so that adjustment thereof may be effected without access to the interior of the machine as a presumption of fraud would obtain if the vote recording mechanism were exposed during election.

One of the objects of this invention is to provide a power transmission latch, or connecting member, which, when adjusted will release the power driving mechanism and effect the operative engagement of the hand operated control members.

Another object of the invention is to provide a coupling member which is organized for operative adjustment within a portion of the machine remote from the vote recording mechanism.

Another object of the invention is to provide a coupling comprising a unitary member which is sturdy of structure, durable and economic of manufacture.

Other objects more or less ancillary of the foregoing and the manner in which all the various objects are realized will appear in the following description which, considered in connection with the accompanying drawings, sets forth the preferred embodiment of the invention.

Referring to the drawings in which a preferred embodiment of the invention is illustrated—

Figure 1 is a transverse sectional view through a fragmentary portion of the base of the voting machine illustrating the election officer's control knob, the latch embodied in the present invention and the actuating mechanism coordinated therewith.

Figure 2 is a vertical section through similar fragmentary portion of the voting machine housing illustrating the officer's control knob, the latch, the driving mechanism and its appurtenances.

Figure 3 is a detail view of the mechanism illustrated in Figure 2, the voting machine hous-

ing being omitted and the latch being shown positioned to effect the disengagement of the electric motor drive.

Figure 4 is a similar view of the mechanism illustrated in Figure 3, the latch being indicated in position to effect the electric motor drive.

Figure 5 is a similar view of the mechanism shown in Figures 3 and 4, the latch being indicated in disengaged position.

Figure 6 is a transverse sectional view taken on a plane indicated on line 6—6 in Figure 3.

Figure 7 is a transverse sectional view taken on a plane indicated by the line 7—7 in Figure 4.

Figure 8 is a horizontal section taken on a plane indicated by the line 8—8 in Figure 5.

Referring to the drawings, and particularly Figures 1 and 2, the voting machine actuating mechanism embodies a reciprocative drive plate 10 having a pair of racks 11 and 12 mounted thereon. The toothed portions of the racks are spaced to provide clearance for the perimeter of a spur gear 13 which is disposed intermediate the racks and mounted for vertical adjustment so that engagement thereof may be effected with either of the racks. The driving plate 10 is guided upon flanged rollers 14 mounted upon a frame member supported within the voting machine housing 15. The spur gear 13 is mounted upon a shaft 16 coupled through universal joints, not shown, to an electric motor. The shaft 16 extends within an inclined opening or guideway 17 formed in a cam plate 18 longitudinally guided by a bracket 19 mounted upon the base 20 of the voting machine cabinet 15. The cam plate 18 is sustained by tension springs 21 mounted upon bell cranks 22 pivotally supported upon a slide in the form of an angle iron 23 mounted for reciprocative movement upon brackets 24 secured upon the base 20 of the voting machine cabinet. The lower arms 25 of the bell cranks 22 engage the base of the angle iron 23 and thus restrain the upper arms of the cranks from movement inwardly.

As illustrated in Figure 6 the slide or angle iron 23 is mounted parallel and in spaced relation with a second slide also in the form of an angle iron 26, the lateral flange of the angle iron 26 being above and opposed to the base flange of the angle iron 23. Intermediate the vertical flanges of the angle irons 23 and 26 there is a latch 27 having a pivot pin 28 rigidly affixed thereto. The outer portion of the pin 28 is provided with an enlarged head 29 diametrically grooved to receive a tongue formed in the portion of a strap spring 30 which is supported upon the

vertical leg of the angle iron 23. The shank of the pin 28 is suitably journaled in an aperture 31 in the angle iron 23 to permit the oscillatory movement of the latch. The free end of the latch plate 27 is formed with an arcuate slot 32, the radius thereof being struck from the center of the pin 28. The slot 32 is adapted for engagement with a latch pin or pindle 34 which extends through a slot 35 formed in the vertical leg of the angle iron 23. Rearward the pin 28 there is a second slot 36a formed in the vertical flange of the angle iron 26 and a similar slot 36 in the flange of the angle iron 23. Within these slots there is a relatively stationary combined latch pin and anchor bolt 37 mounted in the angle clip 24 adjacent thereto. The bolt is provided to support the two angle irons in their assembled relation and at the same time facilitates the reciprocative movement thereof. The rearward face of the latch 27 is provided with an arcuate slot 33 described from the center of the pin 28. The slot 33 is arranged for engagement with the shank of the bolt 37 when the latch is pivotally adjusted to effect such connection. The outer end of the angle iron 26 is connected with the officer's control knob 38, which, as illustrated in Figure 1, is mounted upon a push rod extending through an aperture 39 in the housing 15.

Above the officer's control knob 38 there is an opening 40 having a cover plate 41 thereover which is hinged upon the housing 15 and provided with a suitable key controlled door lock.

In operation, assuming the electric motor drive to be coupled to effect the operation of the machine, the latch 27 is positioned as indicated in Figure 2 with the slot 32 therein engaged with the pindle 34. In this position the latch interlocks the angle irons 23 and 26 so that reciprocative adjustment of the officer's control knob 38 will effect movement of the angle iron 23 and the consequent adjustment of the cam plate 18 through the spring 21 thus causing the elevation or lowered adjustment of the spur gear 13 and the intermeshed engagement thereof with the respective racks 11 and 12. During the voting cycle the rotation of the pinion 13 will cause the translation of the rack 11 until the pinion runs beyond the teeth at the end portion of the rack. Thereupon the election officer presses the control knob 38 inwardly so that the cam plate 18 will cause the gear 16 to engage the rack 12 to effect the return of the plate 10 and thus complete the voting cycle.

The pivotal support of the bell cranks 22 will prevent either of the untensioned springs, during this operation, from arresting movement of the cam plate 18 as the upper arms of the cranks will yield to the thrust of the collapsed spring when pressure is applied thereto.

In the event the electric current should fail or if for some other reason it is desired to couple the machine for hand operation, the election officers unlock the door 41 and adjust the latch 27 in engagement with the bolt 37, as shown in Figures 3 and 6. During such adjustment the angle iron 26 will be disengaged from the angle iron 23, thereby releasing the officer's control knob 38 from operative control of the motor driving mechanism. When the latch is adjusted upon the bolt 37 the angle iron 23 is shifted to a position where the pinion 13 will be disengaged with both the racks 11 and 12, as illustrated in Figure 3, thus releasing the electric motor driving connection.

Although the foregoing description is neces-

sarily of a detailed character, in order that the invention may be completely set forth, it is to be understood that the specific terminology is not intended to be restrictive or confining, and that various rearrangements of parts and modifications of structural detail may be resorted to without departing from the scope or spirit of the invention as herein claimed.

We claim:

1. In a drive mechanism for voting and like machines, means for shifting a movably mounted drive pinion into and out of operative engagement with spaced driven gear members, comprising: a shiftable guide member having an operative connection with said pinion, a manually reciprocable slide, a second slide disposed adjacent said first-named slide and having an operative connection with said guide member, and a latch member adapted when in one of its latching positions to connect said slides to one another whereby the guide member may be manually actuated through the medium of said slides to shift the drive pinion into selective driving engagement with said gear members and when in another of its latching positions to disconnect said slides and at the same time hold the second-named slide and guide member in a position which will maintain the drive pinion in neutral.

2. In drive mechanism for voting and like machines, means for shifting a movably mounted drive pinion into and out of operative engagement with spaced driven gear members, comprising: a shiftable guide plate having an operative connection with said pinion, a reciprocable slide having a manually operated push rod connected thereto, a second slide disposed adjacent said first-named slide and having an operative connection with said guide plate, and a latch member pivotally mounted on one of said slides and adapted when oscillated to one of its latching positions to connect said slides to one another whereby the guide plate may be actuated through the medium of said push rod to shift the drive pinion into selective driving engagement with said gear members and when oscillated to another of its latching positions to disconnect said slides and at the same time hold the second-named slide and guide plate in a position which will maintain the drive pinion in neutral.

3. In drive mechanism for voting and like machines, means for shifting a movably mounted drive pinion into and out of operative engagement with spaced driven gear members, comprising: a shiftable guide plate having an operative connection with said pinion, a reciprocable slide having a manually operable push rod connected thereto, a second slide disposed adjacent said first-named slide and having an operative connection with said guide plate, a latch member pivotally connected to one of said slides and formed with arcuate latching slots therein, a latch pin secured to one of said slides on one side of said latch member and projecting through a slot in the other slide, a relatively stationary pin on the opposite side of said latch member, said latch member when oscillated into latching engagement with said first-named pin functioning to connect said slides to one another to move in unison whereby the guide plate may be manually actuated through the medium of said push rod to shift the drive pinion into selective driving engagement with said gear members and when oscillated to its reverse position into engagement with said second-named pin functioning to disconnect said slides and at the same time

hold the second-named slide and guide plate in a position which will maintain the drive pin in neutral.

4. In drive mechanism for voting and like machines, means for shifting a movably mounted drive pinion into and out of operative engagement with spaced driven gear members, comprising: a shiftable guide plate having an operative connection with said pinion, a reciprocable slide having a manually operable push rod connected thereto, a second slide mounted adjacent to and parallel with said first-named slide and having an operative connection with said guide plate, a latch pivotally connected to one of said slides and formed with arcuate latching slots therein, a latch pin secured to one of said slides on one side of the pivot point of said latch and projecting through a slot in the other slide, a relatively stationary combined latch pin and anchor bolt mounted on the opposite side of the pivot point of said latch member and projecting through slots formed in said slides, said latch when oscillated into latching engagement with said latch pin functioning to connect said slides to one another to move in unison whereby the guide plate may be manually reciprocated through the medium of said push rod to shift the drive pinion into selective engagement with said rack bars, and when oscillated to its reverse position in engagement with said combined anchor bolt and latch pin functioning to disconnect said slides and at the same time move the slide which is connected to said latch plate into a position which will bring the drive pinion into neutral.

5. In a drive mechanism for voting and like machines, means for shifting a movably mounted drive pinion into and out of operative engagement with spaced rack bars, comprising: a reciprocable guide plate having an operative connection with said pinion, a pair of reciprocable slides, one of said slides being connected with said guide plate and the other of said slides having a manually operable push rod connected thereto, an arcuate slotted latch plate pivoted

to one of said slides, a latch pin connected to one of said slides on one side of the pivotal connection of said latch plate and a combined anchor bolt and latch pin mounted on the other side of said pivotal connection and projecting through slots formed in said slides, said latch plate when oscillated into latching engagement with said latch pin functioning to connect said slides to one another to move in unison whereby the guide plate may be manually reciprocated through the medium of said push rod to shift the drive pinion into selective engagement with said rack bars, and when oscillated to its reverse position in engagement with said combined anchor bolt and latch pin functioning to disconnect said slides and at the same time move the slide which is connected to said latch plate into a position which will bring the drive pinion into neutral.

6. In drive mechanism for voting and like machines, means for shifting a movably mounted drive pinion into and out of operative engagement with spaced rack bars, comprising: a reciprocable guide plate having an operative connection with said pinion, a reciprocable slide having an operative resilient connection with said guide plate, a second slide disposed adjacent to and parallel with said first-named slide and having a manually operable push rod connected thereto, and a latch member pivotally connected to one of said slides and functioning when oscillated into one of its latching positions to connect said slides to one another to move in unison whereby the guide plates may be manually reciprocated through the medium of said push rod to push the drive pinion into selective driving engagement with said rack bars and when oscillated to its opposite latching position functioning to disconnect said slides and at the same time shift the drive plate into a position which will bring the drive pinion into neutral.
